P. FRANK

TEMPORARY LOOSE LEAF BINDER

Filed Oct. 8, 1924

INVENTOR

Peter Frank
William A. Smith, Jr.
ATTORNEY

UNITED STATES PATENT OFFICE.

PETER FRANK, OF NEW YORK, N. Y., ASSIGNOR TO KNICKERBOCKER BINDERY, INC., OF NEW YORK, N. Y., A CORPORATION OF NEW YORK.

TEMPORARY LOOSE-LEAF BINDER.

Application filed October 8, 1924. Serial No. 742,452.

To all whom it may concern:

Be it known that I, PETER FRANK, a citizen of the United States, residing at New York, in the county of New York and State of New York, have invented certain new and useful Improvements in Temporary Loose-Leaf Binders, of which the following is a specification, reference being had therein to the accompanying drawing.

10 My invention relates to temporary loose-leaf binders, and has particular reference to an improved means for normally maintaining the inserted leaves in proper position within the binder.

15 An object of my invention is to provide a temporary loose-leaf binder or ledger in which the several leaves of the book may be quickly and conveniently inserted in or removed from the binder and in which a 20 spring-actuated follower or compressor plate is associated with the transverse binding posts to normally clamp the insertion sheets in proper position.

25 A further object of my invention is to provide a temporary loose-leaf binder in which transverse binding posts pass through spaced apertures at or near the marginal edge of the inserted leaves and through spaced apertures in a suitable follower or 30 compressor plate, and to provide novel means cooperating with said follower or compressor plate for normally maintaining the same in contact with the pack of inserted leaves.

35 A further object of my invention is to provide an improved binding post for binders of the type specified, the said posts containing or housing the tension spring connected to the follower or compressor plate for maintaining the same in proper clamping position.

40 A still further object of my invention is to provide a temporary loose-leaf binder of the type specified, which is simple in construction, inexpensive to manufacture, reliable in operation, and strong and durable.

45 In the accompanying drawing forming a part of this specification, and in which like numerals are employed to designate like parts throughout the several views:—

50 Fig. 1 is a perspective view of one form of temporary loose-leaf binder showing my improved posts and compressor plate applied thereto;

Fig. 2 is an enlarged side elevation on 55 the line 2—2 of Fig. 1, showing in detail the construction and operation of the hollow posts and spring actuated compressor plate;

Fig. 3 is a transverse section on the line 3—3 of Fig. 2;

Fig. 4 is a fragmental plan view on the line 4—4 of Fig. 2.

Referring to the drawings, wherein for the purpose of illustration, is shown a preferred embodiment of my invention, the numeral 6 designates a one-piece back or cover of leather or other suitable bookbinding material, on the inner surface of which, at a position near the center thereof, is secured a strip of relatively stiff fabric 7, provided with spaced parallel tucks or guide-ways 8. These tucks or guide-ways 8 are cut away at spaced intervals throughout their length to receive the apertured ends of the transverse binding posts 9, which are pivotally connected to the cover by the removable fastening rods or pintles 10, passing through the tucks or guide-ways 8 and through the apertured ends of the said binding posts 9. By this construction, any or all of the leaves 80 may be readily inserted in or removed from the binder, it being only necessary to withdraw one of the fastening rods or pintles 10 from the tucks or guide-ways 8 and the apertured ends of the several binding posts 9, 85 at which time the previously positioned leaves may be moved off the binding posts 9, or new leaves inserted thereon. All of the above described construction is old and well known in the art and forms no part of my 90 present invention.

In the preferred form of my invention, I provide a novel form of transverse binding post 9, the said post comprising a substantially U-shaped member, the upper arms 95 of which are provided near their ends with axially aligned apertures 11 and the lower connecting portion of which is provided with a transverse aperture 12, the fastening rods 10 passing through the said apertures for pivotally mounting the transverse binding posts 9 to the cover 6 in the manner specified in the preceding paragraph. Near the closed end of the U-shaped binding posts 9 and extending between the 100 spaced arms thereof, I position a transverse pin 13 for a purpose to be hereinafter specified.

For clamping the inserted sheets 14 within the binder and for normally maintaining the pack of sheets in proper position therein, I provide a follower or compressor plate 15, the said follower or compressor plate comprising a thin sheet of metal or other suitable material apertured to pass over the respective arms of the U-shaped binding posts as clearly shown in the accompanying drawings. One end of a coiled tension spring 16 is attached to the transverse pin 13 (previously described) while the opposite end of said spring is attached to that portion of the follower or compressor plate lying between the spaced arms of the U-shaped binding post. As a convenient manner of attaching the end of the spring 16 to the follower or compressor plate 15, that portion of the plate lying between the spaced arms of the U-shaped binding posts may be bent downwardly to form an apertured lug 17 to which the end of the spring may be attached. If desired, I may also employ a second metallic strip 18, provided with suitable spaced apertures for passing entirely over the binding posts 9, it being understood that the pack of inserted leaves 14 is positioned between this second plate and the spring-actuated follower or compressor plate 15 above described.

In the operation of my improved device, the spaced arms of the U-shaped binding posts 9 are inserted through the spaced openings in the compressor plate 15 and the ends of the spring attached respectively to the transverse pin 13 and to the apertured lug 17. The spaced arms of each U-shaped post are now inserted within the spaced openings in one of the tucks or guide-ways 8, and the fastening rod 10 is inserted through the tuck or guide-way 8 and through the alined apertures, 11, thus pivotally mounting the binding posts to the cover 6. The leaves 14 are then placed on the transverse binding posts 9 and as the thickness of the pack increases, the compressor plate 15 is gradually forced along the binding posts 9, against the tension of the coil springs 17. When the desired number of sheets have been inserted, the second metallic strip 18 is placed on the binding posts; the closed ends of the U-shaped binding posts are positioned within the spaced openings in the other tuck or guide-way 8; and the fastening rod or pindle 10 is inserted through this tuck or guide-way and through the apertures 12 in the closed end of the U-shaped posts, and the loose-leaf binder with its inserted sheets is thus secured in assembled relation, with the spring pressed follower or compressor plate clamping the pack of inserted sheets in proper position within the binder.

It will thus be seen that I provide a temporary loose-leaf binder in which the sheets

may be readily inserted in or removed from the binder and in which a spring-actuated follower or compressor plate is employed to normally hold the inserted sheets in their proper clamped position. Now specifically, I have provided a novel form of transverse binding post for binders of the type specified, the said posts constituting the housing or casing for the tension spring employed for actuating the follower or compressor plate.

It is to be understood that the form of my invention herein shown and described is to be taken as preferred example of the same, and that various changes in the shape, size and arrangement of parts may be resorted to without departing from the spirit of my invention or the scope of the subjoined claims.

Having thus described my invention what I claim as new and desire to secure by Letters Patent is:—

1. A temporary loose-leaf binder, comprising a back or cover, hollow transverse binding posts pivotally and detachably mounted on said cover, a compressor plate mounted on said binding posts at one side of the pack of inserted sheets, and resilient means carried within the said hollow binding posts for forcing the compressor plate against the pack of inserted sheets to normally maintain the pack in clamped position within the binder.

2. A temporary loose-leaf binder, comprising a back or cover, U-shaped transverse binding posts pivotally and detachably mounted on said cover, a compressor plate mounted on said binding posts at one side of the pack of inserted sheets, and a coiled tension spring mounted between the spaced arms of each U-shaped binding post and having one end attached to the compressor plate and its opposite end attached near the base of said U-shaped binding posts, whereby the said compressor plate is forced against the pack of inserted sheets to normally maintain the same in clamped position within the binder.

3. A temporary loose-leaf binder, comprising a back or cover, U-shaped transverse binding posts pivotally and detachably mounted on said cover, a transverse pin passing through the arms of each U-shaped post near the base thereof, a compressor plate mounted on the binding posts and having openings adapted to pass over each arm of said posts, and a coiled tension spring mounted within each binding post and having one end attached to said transverse pin and its opposite end attached to that portion of the compressor plate lying between the spaced arms of said U-shaped posts, for normally maintaining the compressor plate in clamping position upon one side of the pack of inserted sheets.

4. In a temporary loose-leaf binder, the combination of a hollow binding post, a compressor plate mounted on said post on one side of the pack of inserted sheets, and a coiled tension spring mounted within the hollow binding posts and attached to the compressor plate for normally maintaining the same in clamping position upon the pack of inserted sheets.
- 10 5. In a temporary loose-leaf binder, the combination of a U-shaped binding post, a compressor plate mounted on said post on one side of the pack of inserted sheets and having spaced openings passing over the 15 arms of said U-shaped binding post, and a coiled tension spring mounted between the arms of the binding post, one end of said spring being attached near the base of said U-shaped post and its opposite end being 20 attached to that portion of the compressor plate lying between the spaced arms of said U-shaped post, for normally maintaining the compressor plate in clamping position upon the pack of inserted sheets.
- 25 6. In a temporary loose-leaf binder, the combination of a U-shaped binding post, a compressor plate mounted on said post on one side of the pack of inserted sheets and having spaced openings passing over the 30 arms of said U-shaped binding post, a de-
- pending apertured lug formed on that portion of the compressor plate between the said spaced openings, and a coiled tension spring mounted within the U-shaped binding post and having one end attached to the post near 35 the base thereof, and its opposite end attached to the said depending lug on the compressor plate, whereby the compressor plate is normally maintained in clamping position upon the pack of inserted sheets.
7. In a temporary loose-leaf binder, the combination of a U-shaped binding post, a transverse pin passing through the arms of the U-shaped post near the base thereof, a compressor plate mounted on said post on 40 one side of the pack of inserted sheets and having spaced openings passing over each arm of the said binding post, a depending apertured lug formed on that portion of the compressor plate between the said spaced 45 openings, and a coiled tension spring mounted within the U-shaped binding post, one end of said spring being attached to the said transverse pin and the other end to said depending lug, whereby the compressor plate is normally maintained in clamping 50 position upon the pack of inserted sheets.

In testimony whereof I hereunto affix my signature.

PETER FRANK.
